[57] ABSTRACT

The switch is incorporated in a magnetic pickup to generate a high level digital signal, improving the signal form and the signal-to-noise ratio. A bistable switch includes input and output stages with a common coupling element having a constant voltage independent of the supply potential, enabling the use of one circuit over a range of operating voltages.

REGENERATIVE TRANSISTORIZED SWITCH WITH CONSTANT VOLTAGE CIRCUIT

This application is a continuation of my application Ser. No. 146,175, filed May 24, 1971, assigned to the assignee of this application, which was a division of Ser. No. 875,983, filed Nov. 12, 1969, now abandoned.

This invention relates to a bistable switch which responds to an input signal to generate a digital (on-off) output. The switch is disclosed in a magnetic pickup, i.e., a sensing device responsive to a change in flux linking a coil. In a typical magnetic pickup a coil has a core of magnetic material with an end projecting from the coil to form a pole piece. A permanent magnet at the rear of the coil establishes magnetic flux which links the turns of the coil. A case surrounds the core and coil leaving only the pole piece exposed. Relative movement between the pickup and a body of magnetic material having a discontinuity causes a change in the flux linking the coil, inducing a voltage in the coil.

A common application of a magnetic pickup is in a system for measuring the speed of a rotating shaft. The pickup is located adjacent a gear on a shaft and senses movement of the gear teeth. The voltage induced in the coil is a function of the coil inductance and the rate of change of flux linking the turns of the coil.

Where the actuator is coarse, as slow moving, widely pitched gear teeth, the output is a series of voltage pulses followed by an exponential decay. With a fine actuator, i.e., rapidly moving closely spaced gear teeth, the output voltage approximates a sine wave. Both the form and amplitude of the output are functions of the relative speed of movement between the pickup and the body being sensed.

The circuit to which the pickup is connected is normally located some distance away with a length of cable extending between them. If the pickup is used in noisy environment, it is susceptible to false actuation through signals inductively or capacitively coupled to the pickup coil or to the associated connecting cable.

The signal generated in the pickup coil is coupled with a switching circuit which has a digital output, of uniform shape and amplitude.

A principal feature of the invention is that the switching circuit has input and output stages with a common coupling element, which has a constant voltage characteristic. Thus, the circuit may be used over a range of operating voltages and has a digital or on-off output with a range between on and off levels which is a function of the source potential.

Yet another feature is that the coupling element is a transistor with its emitter-collector circuit connected in series with the emitter-collector circuits of the input and output transistors and a bias circuit connected from the potential source to its base, causing the coupling transistor to conduct heavily with the emitter-collector saturation voltage stabilizing the switching circuit.

Further features and advantages of the invention will readily be apparent from the following specification and from the drawings, in which:

FIG. 1 is a diagrammatic illustration of a magnetic pickup sensing system;

FIG. 2 is a series of waveforms illustrating operation of the switch;

FIG. 3 is a circuit of one embodiment of the switch;

FIG. 4 is a circuit of a preferred embodiment of the invention;

FIG. 5 is a circuit of a modified embodiment of the invention; and

FIG. 6 is a longitudinal section of a pickup unit incorporating the invention.

The on-off switching circuit which is incorporated in the magnetic pickup unit in accordance with the present invention produces a digital or on-off output. The on-off switching circuit has a novel input bias network that permits high sensitivity and yet is stable over a wide range of operating conditions. The bias network and the connection of the pickup coil in series between the bias source and the switch input provide a high degree of noise immunity.

The digital output of the pickup may be used directly in auxiliary digital equipment, without the need for additional interface equipment to generate the digital signal.

In FIG. 1 a representative pickup unit 10 is illustrated in a system for determining the speed of rotation of gear 11 mounted on shaft 12. The teeth 13 of gear 11 move past the end of core 14 which forms a pole piece 15. A permanent magnet 16 is located rearwardly of core 14 and establishes a magnetic field through it. Coil 17 surrounding core 14 is linked by the flux from magnet 16.

As teeth 13 of the gear move past pole piece 15 the reluctance of the magnetic path to flux from magnet 16 varies and thus the total flux linking coil 17 varies. The resulting voltage induced in coil 17 is connected through conductors 20 with a utilization circuit 21.

Details of the utilization circuit form no part of the invention and will not be illustrated. Many suitable circuits are known.

In FIG. 2 the outputs of prior art magnetic pickups are illustrated by curves 25 and 26. With a coarse actuator the output waveform 25 is a series of alternate positive and negative pulses with low levels of positive and negative voltage between successive pulses due to small increases and decreases in flux linking the coil. With a fine actuator, as gear 13, the output waveforms 26 approximates a sine wave.

The digital output of the pickup incorporating the invention is illustrated by rectangular waveforms 27 and 28 which will be described in more detail in connection with the description of the circuits.

During the course of the following description, specific type designations and the component values will be given for operative circuits. The purpose of this specific disclosure is to illustrate operative embodiments of the invention. The values and relationships are not critical unless otherwise specified.

One form of the switch is illustrated in FIG. 3. A transistorized switching circuit 30 has an input stage 31 and an output stage 32, each a type D26C2 transistor. The circuit is powered from a suitable source of positive potential, B+, the negative terminal of which is connected with a reference potential or ground 33. The emitters of transistors 31 and 32 are connected together through a common or coupling impedance element, resistor 34, to ground. The collectors of both transistors are connected through resistors 35, 36, with B+. The base input element of output transistor 32 is connected with the collector of transistor 31.

The input transistor 31 is normally held in a non-conductive condition. A bias is applied to the base through a network including resistor 38, in series with a diode connector transistor 39 across the power supply. The junction between resistor 38 and diode 39 is connected through the pickup coil 40 with the base of input transistor 31. When no signal is induced in coil 40, input transistor 31 is cut off and output transistor 32 conducts. The emitter of input transistor 31 is held positive by the current of transistor 32 flowing through common emitter resistor 34. The base bias developed across diode 39, however, is equivalent only to the base to emitter potential drop of the transistor and accordingly the base is negative with respect to the emitter, and input transistor 31 does not conduct. The output terminal 41 is essentially at ground potential.

When a voltage is induced in pickup coil 40 such that the right hand terminal 42 thereof, connected with the base of transistor 31, is positive with respect to the left hand terminal 43 by an amount sufficient to make the base positive, transistor 31 is caused to conduct. When this occurs, the voltage at the collector drops and output transistor 32 is cut off. The potential at output terminal 41 rises to the value of the power source, B+. So long as the base of the input transistor remains positive with respect to the emitter, the input transistor conducts and the output remains high. However, when the voltage at the base of the input transistor drops to a value near zero, the condition of the circuit rapidly reverses, transistor 31 ceasing conduction and transistor 32 conducting heavily. The voltage at output terminal 41 returns to a low level.

The operation may be compared with that of a prior art pickup by comparing curves 25-27 and 26-28. The voltage curve 25 represents the signal induced in coil 40. When the coil output is high in a positive sense, the output at terminal 41 is high. When the signal induced coil drops to zero, the output falls to zero. No output is obtained from the negative pulse. Similarly, comparing curves 26 and 28, when the coil output (26) is positive, the output from terminal 41 shown by curve 28 is high. When the coil output is negative, output terminal 41 is low.

Diode connected transistor 39 is preferably of the same type as transistor 31 so that the characteristics of the base emitter diodes track with temperature change. The relationship of these characteristics is extremely important in maintaining the level of sensitivity of the pickup.

The output derived from the switch circuit at terminal 41 may be utilized as an input for digital utilization circuitry, as a counter or the like. The input voltage requirements of the circuitry to which the signal is connected determine the potential to be utilized in the power supply. The circuit of FIG. 3 when utilizing a 5 volt source has resistors 35, 36 and 38 with a value of 1,000 ohms. Resistor 34 is 2.7 ohms. If the source voltage is changed, resistors 35, 36, 38 must be changed. For example, with a 12 volt source, these resistors have a value of 2,200 ohms.

The circuit of FIG. 3 may be operated with conditions of very high sensitivity by virtue of the bias network for the input transistor 31 and the connection of the coil 40 in series between the anode of the bias diode (the collector of the transistor 39) and the base of transistor 31, rather than in some other configuration as shunted across the base-emitter circuit of transistor 31,

for example. These two features contribute to a noise immunity which enables operation of the switching circuit with a low level of input signal. The switching circuit is subject to actuation from an off to an on condition only with one polarity of signal. Thus, 50 percent of the random noise is ineffective to turn the circuit on. As most utilization circuitry can make use of the turn on indication of the switching circuit (the shift of output terminal 41 from a low to a high condition), the turn off condition is relatively unimportant.

The principal source of noise is from signals inductively coupled to coil 40. As the coil is not returned to ground but floats between the bias diode and the transistor, the spurious signal appears at both terminals and the voltage coupled to the base of transistor 31 is not affected. A second source of interference is from signals induced in the power lead connected with B+. Positive signals at this point are effectively shorted to ground by diode connector transistor 39. As a result of this noise immunity, the sensitivity of the circuit with the components described above, may be of the order of 10 millivolts, as contrasted with a signal of the order of 700 millivolts which might be required to trigger a conventional switching circuit.

The turn off signal level may typically be about one-half of the turn on signal level. Thus, if transistor 31 is caused to conduct with a positive signal of 10 millivolts at its base, it will turn off when that signal falls below 5 millivolts. This hysteresis effect accounts for the non-symmetrical relation between rectangular wave 27 and the output of the coil with a coarse actuator, illustrated by curve 25.

The stability of the circuit may further be enhanced by the addition of a ground return resistor 44 from the base of transistor 31 to ground 33. In a typical circuit this resistor could have a value of 10,000 ohms.

It is convenient, particularly from a manufacturing standpoint, to have one circuit which may be utilized with a range of source voltages. Such a circuit is illustrated in FIG. 4. Elements common with those in FIG. 3 are given the same reference numerals.

The common emitter impedance element (resistor 34 in FIG. 3) is replaced by a transistor 46 which has its emitter collector circuit connected in series with the switching transistors 31, 32, between the common emitter connection and ground 33. The base of transistor 42 is connected through resistor 47 with B+. The positive potential on the base of transistor 46 keeps it in a saturated condition. In this condition the steady state collector-emitter voltage is essentially constant regardless of the current. Thus, the emitter of input transistor 31 is maintained at the same voltage level with respect to ground over a range of source of voltages. The emitter potential of transistor 31 is a measure of the sensitivity of the switching circuit and, with the common emitter coupling transistor 46, this sensitivity remains essentially the same over a range of source voltages. Notwithstanding the steady state constant voltage characteristic of saturated transistor 46, a transient voltage increase occurs when a change in the input signal level initiates a switching action. The voltage increase enhances the rapid switching action described above.

In a representative embodiment of the circuit, transistors 31, 32, 39 and 42 are each General Electric type D26C2. Resistors 35, 36, 38 and 47 are 4,700 ohms.

The circuit is capable of operation with an input or source voltage from 4 to 15 volts.

The circuit will operate from a negative source voltage by substituting PNP transistors for NPN transistors. The relationship of the output signal to the movement of the actuating body relative to pickup coil 40 may be reversed by deriving the output from transistor 31 rather than transistor 32.

Pickup coil 40 is designed to have a positive output, i.e., terminal 42 is more positive than terminal 43 upon the entry of a body of magnetic material into the sensing field. In certain sensing situations the object being sensed is actuated by operation of a DC solenoid. Where the solenoid coil and the magnetic pickup coil are in close proximity, a signal is coupled into the pickup coil upon energization and de-energization of the solenoid. If this induced signal is positive and the orientation of the coils cannot be arranged to eliminate undesired coupling, the polarity of biasing magnet 16 and the winding sense of pickup coil 17 (40) may both be reversed. The relationship of the output of the pickup coil to the movement of the sensed object remains the same while the signal induced in the coil from the interference source is reversed in polarity and tends to turn the first stage of the switch off rather than on.

The amplitude of the voltage induced in pickup coil 40 is a function of several variables. Where the object being sensed is relatively slow moving and widely spaced from the coil, the level of the output voltage may be increased by using a magnet with greater coercive force or increasing the number of turns on the pickup coil. However, when such a pickup is used with a fast moving closely spaced object, the voltage induced in the pickup coil may be quite large and, in some cases, of sufficient amplitude to damage transistors 31 and 39. FIG. 5 illustrates a circuit in which the output of the pickup coil is limited to reduce the danger to the transistors from excessive voltage in the pickup coil. Circuit elements which have been described in connection with FIGS. 3 and 4 are assigned the same reference numerals and will not be described again. In the preferred form of the circuit reversely connected diodes 50 and 51 are in parallel with the pickup coil 40 and limit the voltage which may appear across its terminals to the forward conduction potential of the diodes. When terminal 42 is positive with respect to terminal 43, diode 52 conducts while diode 51 conducts with the opposite polarity condition.

An alternate to the diodes 51, 52 which eliminates the danger to transistors 31 and 39 as a result of an excessive back bias of the base emitter junctions, is provided by diodes 53, 54 connected as shown in broken lines from the terminals of pickup coil 40 to ground. When either of the terminals become sufficiently negative with respect to ground, conduction of the diodes clamps the voltage level and prevents the establishment of damaging potentials on the transistors.

A preferred physical embodiment of the invention is illustrated in FIG. 6. The trigger circuit and bias network are an integrated circuit on a substrate 50 located within shell 51. The pickup coil 40 is located at the forward end of shell 51 and core 52 projects outwardly therefrom. Permanent magnet 53 is located immediately to the rear of core 52. Leads 54, 55 connect coil 40 with terminals 56, 57 on substrate 50. The integrated circuitry is in the center of the substrate and is

covered by an insulating coating 58. Three terminal areas 59, 60 and 61 at the rear of substrate 50 provide for connection through a three wire cable 62 with the operating potential source and from the output of the switching circuit to a utilization circuit.

I claim:

1. A transistorized switch responsive to an actuating signal and having a digital signal output, comprising: an input circuit, including a source of actuating signal;

a source of operating potential with respect to a reference potential;

bistable regenerative electronic switch means having input and output transistor stages, each with a control element, a common circuit and an output circuit, the control element of the output stage being connected with the output circuit of the input stage, the output and common circuits of both stages being connected between said source of operating potential and said reference potential, the control element of the input stage of the switch means being connected with said source of actuating signal, a common impedance means connected between said common circuits of both stages and directly with said reference potential, said common impedance means comprising the emitter-collector circuit of a transistor, and a resistor connecting the base of the common impedance transistor with said reference potential forwardly biasing the common impedance transistor to saturation, each stage of the switch means having stable, complementary conductive and nonconductive conditions, said saturated transistor common impedance means having a constant voltage characteristic with different levels of current therethrough under steady state circuit conditions, and being subject to a transient variation in voltage, providing regeneration between the sections of the switch, when switching action is initiated by an actuating signal from said source; and

means connected with an output circuit of the switch means for deriving therefrom a digital signal which is a function of the actuating signal.

2. The switch of claim 1 in which the transistors of said switch means each have a base control element and an emitter-collector output circuit.

3. The switch of claim 1 in which the input circuit includes a bias stabilizing means connected with the control element of the input transistor to establish one of the stable conditions of said switch means.

4. The switch of claim 3 in which said bias stabilizing means includes a voltage divider connected across said source of operating potential and having an intermediate point connected with the control element of the input transistor.

5. The switch of claim 4 in which said voltage divider is a resistor connected in series with a forward biased diode across said potential source, the junction between the resistor and diode being connected with the base of the input stage transistor.

6. The switch of claim 2 in which said source of operating potential provides a direct potential and has positive and negative terminals, the emitter-collector output circuits of said input and output stages being connected in parallel from one terminal to a common junction and from said common junction through the series

connected emitter-collector circuit of said common impedance transistor to the other of said terminals.

7. The switch of claim 2 including a first current limiting resistor, a second current limiting resistor, said source of operating potential providing a direct potential and having positive and negative terminals, the emitter-collector output circuits of said input and output stages being connected respectively through said first and second current limiting resistors, in parallel from one terminal to a common junction and from said common junction in series through the emitter-collector circuit of said common impedance transistor to the other of said terminals, and a resistor connecting the base of said common impedance transistor to a power supply terminal, forwardly biasing said common impedance transistor to saturation, the emitter-

collector circuit of the common impedance transistor being connected directly with the other terminal of said power source.

8. The switch of claim 7 in which the input circuit includes a bias stabilizing means connected with the control element of the input stage transistor to establish one of the stable conditions of said switch means, said bias stabilizing means including a voltage divider having a resistor connected with said one power supply terminal and a forwardly biased diode connected in series with said resistor to the other of said power supply terminals, the junction between the resistor and diode being connected with the base of the input stage transistor.
